UNITED STATES PATENT OFFICE.

ALTON F. DINSMORE, OF NEEDHAM, MASSACHUSETTS, ASSIGNOR TO AMERICAN PIANO COMPANY, OF NEW YORK, N. Y., A CORPORATION OF NEW JERSEY.

PIANO-DESK SUPPORT.

Application filed July 19, 1922. Serial No. 576,033.

To all whom it may concern:

Be it known that I, ALTON F. DINSMORE, a citizen of the United States, residing in Needham, county of Norfolk, State of Massachusetts, have invented an Improvement in Piano-Desk Supports, of which the following is a specification.

The present invention relates to music racks for grand pianos and more particularly to an improved device for maintaining the music desk in elevated position for use.

The music rack of a grand piano ordinarily comprises a music desk hinged at one edge and provided with means which in use supports the desk in operative position. It is desirable although not essential that the supporting means should operate automatically, that is to say, it should be caused to assume its operative or inoperative position by the mere opening or closing of the music desk. It is important that the rack should be so constructed that no part of it will vibrate loosely against another part or chatter when the piano is played whether the music desk is in open or closed position.

It is an object of the invention to provide means for maintaining the music desk in elevated operative position which will satisfy the requirements of use and which can be manufactured economically and expeditiously. This and other objects of the invention will more fully appear from a description of a particular illustrative embodiment thereof, reference being had to the accompanying drawings in which,

Figure 1 is a sectional view of a music rack showing the music desk in elevated operative position for use.

Figure 2 is a similar sectional view showing the desk in folded position.

Figure 3 is a plan view of so much of the desk as is necessary to show the brace arrangement and showing the parts in the position indicated in Figure 2.

The structure shown for purposes of illustrating the invention is a music rack having parallel front and rear rails 5, 6 connected to end members 7, of which only one is shown in the drawing, and a music desk 8 hinged to the rear edge of the front rail 5. The front rail is formed to provide a rest 10 which cooperates with the music desk 8 when in open position to support the music. The desk is sustained in its elevated

operative position by a strut 15 which by virtue of a sliding connection moves to collapsed or folded position as the desk is folded forwardly and downwardly. In the particular structure shown the strut is hinged at 60 one end to the rear rail 6 at 16 and is slidably connected to the rear of the music desk by means of a guide or plate 17 having a slot 18 through which the head 20 of the strut 15 extends, a recess 19 being provided 65 in the back of the desk 8 to afford clearance for the head. The hinge connection as shown comprises a leaf 21 which is secured to the under side of the rear rail 6 and extends forwardly against its front edge. During 70 the opening and closing of the music desk there is a relative angular or pivotal movement between the strut 15 and the plate 17, the clearance between the head 20 and the shoulder 22 on the strut being sufficient for 75 this purpose. If desired, the head 20 and shoulder 22 may be so designed and proportioned that as the head reaches the upper end of the slot upon the opening of the desk as in the position shown in Figure 1, the 80 parts will bind more or less and thereby prevent any rattle due to vibration as the piano is played.

It is necessary that when the music desk is in closed position the strut 15 should be prevented from vibrating loosely against the slotted plate 17. In the arrangements illustrated the hinge 16 of the strut is sufficiently below the level of the top of the plate 17 when the music desk is in folded position so 90 that the under face of the strut will bear firmly against the top of the plate 17 at its rear end as indicated at 25 and also against a pad 26 provided on the music desk for this purpose thus bringing the head 20 firmly against the lower surface of the slotted plate. By this arrangement the strut member bears against the slotted plate at two points with a substantial force but in opposite directions so that it is held against rattling thereby. The strain is so adjusted that it is not sufficient to lift the music desk from the pad 27 on which it bears.

The structure described is to be understood as merely illustrative for it is obvious that numerous variations may be made within the scope of the following claims.

1. In a music desk arrangement for pianos, the combination with a support and a music desk hinged thereto of a foldable

brace for supporting the desk in open position, comprising a strut member hinged at one end to the support and slidably connected at its other end to the rear side of 5 the desk.

2. In a music rack for pianos, the combination with a support and a music desk hinged thereto of collapsible means for holding the desk in elevated operative position which comprises a strut between the 10 desk and the support acting in compression to maintain the desk in elevated position and pivoted at one end to one and slidably connected at its other end to the 15 other.

3. In a music rack for pianos, the combination with a support and a music desk hinged thereto of collapsible compression means for holding the desk in elevated operative position which comprises a strut pivotally connected at one end to the support and 20 at the other end slidably connected to the back of the music desk.

4. In a music rack for pianos, the combination with a support and a music desk hinged thereto of collapsible means for holding the desk in elevated operative position which comprises a strut between the desk 25 and the support acting in compression to maintain the desk in elevated position and pivoted at one end to one and slidably connected at its other end to the other the relation of parts being such that when the desk 30 is in folded position the strut is held in strained position whereby rattling thereof is prevented when adjacent parts vibrate. 35

5. In a music rack for pianos, the combination with a support and a music desk hinged thereto of collapsible means for holding the desk in elevated operative position which comprises a guide secured to the 40 music desk, a compression strut hinged to the support at one end and at its opposite

end slidably connected to said guide, and means whereby the connection between the 45 strut and guide may hold the strut against vibration when the music desk is in folded position.

6. In a music rack for pianos, the combination with a support and a music desk hinged thereto of collapsible means for holding the desk in elevated operative position which comprises a guide secured to the music desk, a brace slidably connected at 50 one end to the guide to permit a limited pivotal movement relative to the guide and hingedly connected at the other end to the support, and means whereby the music desk in open position causes the strut to assume one extreme of its pivotal movement relative 55 to the guide and the desk in closed position causes the strut to assume the other extreme of its pivotal movement relating to the guide.

7. In a music rack, the combination with 60 a support and a music desk hinged thereto of a collapsible brace for supporting the desk in open position comprising a slotted plate rigidly secured to the rear face of the music desk, a strut member hinged at 70 one end to the support having slidable engagement with the slotted plate the length and arrangement of the plate and strut member being such that when the music desk is in raised operative position the strut member will abut against the end of the slot to support the music desk and when the desk is in lowered position it will bear against the slotted plate at two points but with pressure in opposite directions to prevent 75 80 vibration thereof.

In testimony whereof, I have signed my name to this specification this 17th day of July, 1922.

ALTON F. DINSMORE.
